UNITED STATES PATENT OFFICE.

GEORGE W. JACQUES, OF STRATFORD, CONNECTICUT, ASSIGNOR TO THE SINGER MANUFACTURING COMPANY, A CORPORATION OF NEW JERSEY.

FASTENER-FEED MECHANISM.

Application filed October 31, 1917. Serial No. 199,500.

To all whom it may concern:

Be it known that I, GEORGE W. JACQUES, a citizen of the United States, residing at Stratford, in the county of Fairfield, and 5 State of Connecticut, have invented certain new and useful Improvements in Fastener-Feed Mechanisms, of which the following is a specification, reference being had therein to the accompanying drawings.

10 This invention relates to fastener feed mechanism for use with automatic fastener setting machines and more particularly to an improved receptacle or hopper for holding and discharging in succession the fasteners which are to be fed to the setting mechanism.

One object of the present invention is to so construct a fastener supply hopper that it shall be free from any propensity to become 20 choked at its discharge opening by reason of the weight of the mass of fasteners contained therein, such choking being a common defect and source of annoyance in the operation of devices of this type as at present employed.

25 Another object of the invention is to provide means for insuring a constant supply of fasteners to the hopper, such means in the present disclosure comprising a secondary reservoir of large capacity arranged to automatically feed fasteners to the hopper, it being understood that it is within the scope of the invention to substitute other and equivalent means for said secondary reservoir.

Another object of the invention is to so 35 relatively arrange the hopper and secondary reservoir as to permit at all times a free and unobstructed passage for flow of fasteners between the same, while at the same time providing against any tendency toward over- 40 loading of the hopper.

Other objects and advantages of the present invention including desirable details of constructions and improved combinations of parts will be hereinafter more particularly 45 described and claimed.

A preferred embodiment of the invention is herein illustrated in the accompanying drawings in which:—

50 Fig. 1 is a perspective view from above showing the hopper and supply reservoir, portions of the hopper being broken out to show the interior construction.

Fig. 2 is a detail sectional view through the discharge opening of the hopper, show-

ing in section the narrow chamber or channel for fasteners.

Fig. 3 is a detail side elevation of the discharge end of the supply reservoir.

1 indicates a bracket mounted as by means of bolts 2 and 3 upon a suitable supporting member 4 carried by the frame of the machine to which the herein described mechanism is to be applied. The bracket 1 is provided with an outwardly extending arm 1^a, said arm having at its outer extremity a bearing 5 within which is mounted a sleeve-member 6. Integrally or otherwise connected to said sleeve-member is a base plate 7, such base plate forming the floor of the fastener-containing hopper. Mounted upon said base 70 plate 7 in any suitable manner, as by means of brackets 8^a, screws 8^a and wing nuts 8^b, is a cylindrical drum 8, said drum being formed at its upper end with a head or cover 9, herein shown as integral with said 75 drum, the cover 9 being provided with an enlarged opening 10.

Within the sleeve 6 is a rotatable shaft 12 which may be constantly driven from any convenient source of power. Fixedly mounted upon the upper extremity of shaft 12 is an enlarged boss, herein shown as comprising a hollow cylinder 11 having an integral head 11', it being understood, however, that it is within the scope of the present invention 80 to make said boss as a solid member or in any other desired manner. Formed in the lower portion of the cylindrical member 11 of the boss is a series of openings 14, said openings being provided for the reception 90 of brush tufts 15 which may be secured within said openings in any desired manner, as by means of set screws 13, the rotating boss with its brush tufts thus providing an agitator for fasteners contained within the 95 hopper.

The cylindrical drum member 8 is provided at one side and just above the base plate 7 with a discharge opening 15', the vertical extent of which may be varied by 100 means of an adjustable apron-member 16 secured in place by set screw 17. Mounted upon the base plate adjacent the discharge opening as by means of brackets 19 is a support 18 for a gate-member, said gate-member 105 acting to regulate the discharge of fasteners from the hopper to a race way indicated generally by the reference numeral 20.

The base plate is shown as provided at a point directly below and extending inwardly from the discharge opening with a depressed area 21 which merges at each end 5 by means of gradual inclines, of which one is indicated at 22, into the body of the base plate. As will be noted from inspection of Fig. 2 the brush tufts may be so arranged as to tend to incline downwardly with respect to the axis of rotation of the agitating device, and in passing the depressed area the outer extremities of said tufts are presented centrally of the discharge opening, thus serving to cause an equal distribution of 10 fasteners to both the upper and lower portions of the discharge opening. Furthermore, by the provision of the depressed area in the base plate adjacent the discharge opening, the vertical height and thereby the 15 cross sectional area of the hopper at this point is increased, serving to give greater freedom of motion to the mass of fasteners which is being swept past the opening by the agitating device, choking of the discharge opening by jamming of the fasteners therein being thus to a great extent prevented.

From inspection of Fig. 2 it will be seen that the concentric cylinders 11 and 8 together with the base plate 7 form a relatively narrow chamber 23 constituting a hopper of annular form. This relatively narrow chamber forms a hopper of limited capacity in which only a comparatively small number 30 of fasteners may be retained at any one time. The fasteners at the lower portion of the hopper are not therefore subjected to any appreciable pressure due to the weight of a large superincumbent mass of fasteners 35 thus serving to overcome a defect common to hoppers at present employed in which the fasteners at the lower portion of the hopper and passing the discharge opening are pressed down by the large mass of fasteners 40 above them which tends to cause jamming and choking at the discharge opening. Moreover, by reason of the fact that the entire inner wall of the hopper is rotating, a more uniform agitation of fasteners contained therein is secured, which results in 45 providing for a freer flow of fasteners to and through the discharge opening.

As is the common practice in fastener feed hoppers the axis of the hopper herein disclosed is inclined to the vertical, thus producing an inclination of the base or floor of the hopper. As herein shown, the discharge opening is so located that fasteners traveling by the same along the floor 55 of the hopper are moving along a downward incline.

At the point 24 in the top or head 9 of the drum member 8 is formed a feed opening, such opening being located above that 60 portion of the base of the hopper which

is inclined upwardly in the direction of the travel of the fasteners passing over the same,—that is to say, fasteners in passing said feeding opening 24 are moving in an uphill direction.

Upon a suitable bracket 27 is supported a supply reservoir 25, herein shown as a box of more or less rectangular form and of relatively large capacity, said box being provided at 26 with a supply opening, having a suitable cover, and with a discharge opening 28 in one end of its bottom. Surrounding said opening 28 is an annular boss 29, said boss being provided at 30 with a projecting flange or lip. In the present device the box 25 is adapted to rest loosely upon the supporting bracket 27, and to have its lip 30 projecting into the opening 24 and beneath the head 9 of the drum 8, the lip thus serving to properly register the openings 24 and 28. The box 25, however, is freely removable for refilling or repairs. At the point 31 an opening has been provided in the box 25 for inspection of the 70 contents thereof, said opening being provided with a piece of glass or other transparent medium permitting ready inspection of the interior.

While the above mode of supporting said box 25 and registering the openings 24 and 28 is a preferred arrangement it is to be understood that it is within the scope of this invention to employ any other equivalent means for accomplishing the desired result.

While it has been heretofore proposed to 100 provide fastener feed hoppers with supply reservoirs, it has in many cases been found difficult to insure a proper flow of fasteners from said reservoir to the hopper and although varied expedients have been resorted 105 to for overcoming this defect, such for example as manual or automatically movable valves between the two receptacles, or the provision of means for adjusting one receptacle with respect to the other, none of 110 these so far as is known have been entirely satisfactory.

Experience has shown that with the hopper inclined as herein above described and with the discharge opening of the feed reservoir located at a point at which the fasteners in the hopper are moving in an upward direction, the opening between the two receptacles may be left entirely unobstructed and yet a free and constant supply of fasteners to the hopper may be secured, while at the same time avoiding any overloading or choking of the hopper.

The above effects may be noted in feeding a hopper of usual form at the point indicated, but the results obtained are particularly satisfactory when a hopper of the type herein shown is employed, that is to say, an annular hopper having a depressed area opposite the discharge opening, the incline 120

leading from the depressed area upwardly to the floor of the hopper accentuating, it being believed, the action which results from the general upward inclination of the floor of 5 the hopper adjacent the feed opening.

While the above description covers a preferred embodiment in the invention, it is to be understood that the scope of the invention is not to be limited thereby but that various 10 changes and modifications in structure and form are embraced therein.

Having now described the invention I claim as new and desire to secure by Letters Patent of the United States:—

15 1. A hopper for fastener-setting machines comprising a base-member, a cylindrical drum mounted on said base-member and having a head provided with a relatively large central opening affording a bearing, and a 20 rotary imperforate cylindrical member disposed within said drum and fitted to said central bearing opening, said cylindrical member being coextensive in length with said drum and forming with the walls of 25 said drum an annular fastener-receiving space, and fastener agitating means in said space.

2. A hopper for fastener-setting machines comprising a base-member, a cylindrical 30 drum mounted on said base-member, a rotary cylindrical member having imperforate walls between which and the walls of said drum is formed an annular fastener-receiving space, said base being provided with a 35 central opening affording a bearing, means extending through said bearing and connected to said cylindrical member for rotating the same, and fastener-agitating means in said fastener-receiving space.

40 3. A hopper for fastener feed mechanism comprising a base member, a drum mounted thereon, a rotatable shaft passing through said base and into the drum, an enlarged boss upon said shaft within the drum. 45 said boss in cooperation with the drum forming a relatively narrow annular channel of substantially uniform width for the recep-

tion of fasteners and means for agitating fasteners in said channel.

4. An annular hopper comprising, in combination, a base member, a fixed cylindrical member forming the outer wall and having a discharge opening, a constantly rotating imperforate cylindrical member forming the inner wall and agitating means for said hopper. 50 55

5. In combination in a fastener feeding mechanism, a hopper comprising a drum having an opening in its upper surface, a detachable fastener reservoir having a discharge opening in its lower surface, and a lip projecting from said lower surface and adapted to enter the drum and to engage beneath the upper surface thereof whereby to ensure registry of said openings. 60 65

6. In combination in a fastener feeding mechanism, a hopper providing a chamber for fasteners, a base or floor for said hopper having an upwardly inclined portion, means for moving said fasteners on said base, and 70 means for supplying fasteners to said hopper at a point adjacent said inclined portion and where said fasteners are being moved upwardly.

7. A cylindrical hopper for fastener setting machines, having an inclined base or floor, a rotary agitator within said hopper acting to move fasteners contained therein in a circular path over said base or floor, and means for supplying additional fasteners to 80 said hopper at a point at which the path of movement of the fasteners contained therein is upwardly inclined. 75

8. In combination, in a fastener mechanism, a hopper providing a chamber for fasteners, a relatively stationary floor for said hopper having higher and lower portions, means for moving said fasteners from one to the other of said floor portions, and means for supplying fasteners to said hopper at a 90 point where such motion is taking place. 85

In testimony whereof, I have signed my name to this specification.

GEORGE W. JACQUES.
